Design No 390.—

John C. Davis
Design for Stoves
Patented 8th July 1851.—

Fig. 3.

Wes. 390

Wm C. Davis: Cincinnati Ohio:
Letters Patent No. 390. dated July. 8. 1851.

The Schedule referred to in these Letters Patent and making part of the same

To all whom it may concern:

Be it known that I Wm C. Davis of Cincinnati, in the County of Hamilton and State of Ohio, have invented or produced a new ornamental design for stoves, of which the accompanying drawings are a correct representation - Fig. 1 representing the plate in front of the fire chamber - with one of its contained fire doors - the other being left out as the two are counterparts of each other. Fig. 2 shows the side plate - with its contained oven-door and fire panel. Fig. 3 is a front view of one of the legs.

Each plate is bordered with a moulding

(a) The panels (b) on each side of the fire doors and the panel (c) at the end of the fire chamber and the central panels (d) of the doors are all decorated with flutes radiating from a central oval or other shaped nucleus (e) in the manner shown.

Each door is decorated with a border moulding (f) as shown.

The upper portion of the leg has an oval panel ornamented with flutes (g) radiating from a central nucleus (h) and the lower portion with ribs (i).

Having described and represented my ornamental design for stoves I wish it to be understood that I do not claim the radiating ornaments or the mouldings separately considered, But what I do claim is the combination of the ornaments as described and represented. In testimony whereof I have hereunto set my hand before two subscribing witnesses.

Witnesses:
